NICHOLAS STARR, JR., OF HOMER, NEW YORK.

Letters Patent No. 77,120, dated April 21, 1868.

IMPROVEMENT IN HORSE HAY-FORKS.

The Schedule referred to in these Letters Patent and making part of the same.

TO ALL WHOM IT MAY CONCERN:

Be it known that I, NICHOLAS STARR, Jr., of Homer, in the county of Cortland, and State of New York, have invented certain new and useful Improvements in Hay-Elevators; and I do hereby declare that the following is a full, clear, and exact description of the same, reference being had to the accompanying drawings, making a portion of this specification, in which—

Figure 1 is a side view of a hay-fork or elevator made according to my invention, showing the same in a closed position.

Figure 2 is a side view thereof, showing the same in an expanded condition.

Figure 3 is an edge view of the same.

Similar letters of reference indicate corresponding parts in all the figures.

This invention relates to that variety of hay-elevating devices known as harpoon-forks, and its object is to provide an elevator which will not only be very simple and strong in construction, but which may also be forced into the hay and otherwise manipulated, when in use, with much greater convenience than those hitherto made.

The invention consists in two lifting-spurs, pivoted at the lower end of a suitable stock, in combination with a sliding bar and toggle-braces, whereby the operation of lifting and discharging the hay, or like material, may be very readily performed.

The invention further consists in the construction of the elevator with a sharp or cutting-edge at its lower extremity, in such manner that it may be forced into the mass of hay to be lifted with very great ease and facility.

To enable others to understand the construction and operation of my invention, I will proceed to describe it with reference to the drawings.

A represents a stock, which may be formed from a flat metal bar bent double, as shown more fully in fig. 3, with a space between the two sides for the reception of the internal portions of the apparatus. Placed in the lower part of the space just mentioned, and pivoted at their lower extremities to the corresponding end of the stock A, are two lifting-spurs, a, the upper ends of which are connected by two toggle-braces or bars, b, in such manner that when the inner ends of the said bars are moved upward, the spurs a will be drawn inward nearly or wholly within the space between the two sides of the stock, and when moved downward, into line with each other, will force the aforesaid spurs laterally outward, and sustain the same in the position shown in fig. 2.

A flat bar or rod, c, is situated within the stock, with its lower end pivoted to the inner ends of the toggle-braces a. The upper end portion of this rod c is furnished at one side with lips, c', folded over the adjacent edges of the sides of the stock, and the office of which is to steady the upper part of the aforesaid rod during the movements of the same. The said stem is furthermore furnished with a lug, b', to which is attached a tripping-cord, d, which passes over a pulley, e, placed in the upper part of the interior of the stock.

The lower portion of the rod c has formed in it a longitudinal slot, c', through which passes a transverse pin, d', secured in the stock, and which serves as a guide for the rod during the movements of the same.

Provided at the upper end of the stock is a ring or loop, g, to which the draught-rope m is attached.

The lower extremity of the apparatus is bevelled off at each side, to form a cutting-edge at the said extremity, as shown at g', the said edge being formed preferably upon the somewhat projecting edge or end of the lower portion of one of the spurs a.

The apparatus being in the position shown in fig. 1, the lower portion thereof is thrust down into the mass of hay to be elevated, such forcing of the elevator into the hay being rendered very easy and convenient by the sharp edge formed upon the lower end thereof, as described. The rod c is then forced downward, and, acting through the toggle-bars b, forces the lifting-spurs a laterally outward into the position shown in fig. 2, the said toggle-braces being brought into line with each other, thus firmly sustaining the spurs in the position described. The elevator being drawn up by the draught-rope m, the spurs b, catching underneath a greater or less quantity of hay, lift or elevate the same, as the fork is drawn upward, until, the desired elevation being attained, the

tripping-cord is pulled, thereby forcing upward the inner ends of the toggle-braces, thereby bringing the aforesaid spurs into the space between the sides of the stock, thus releasing the hay, which, of course, falls from the elevator by its own weight. The lifting-spurs being thus brought to their original position, the elevator may be again inserted into the mass of hay, to elevate, in like manner, another portion of the same.

What I claim as my invention, and desire to secure by Letters Patent, is—

The two spurs, *a*, pivoted at their lower ends to the stock *A*, in combination with the shifting-bar *c* and toggle-braces *b*, substantially as herein set forth, for the purpose specified.

NICHOLAS STARR, JR.
